(57) **CLAIM**

The ornamental design for a fire pit, as shown and described.

DESCRIPTION

FIG. 1 is a front, right, and top perspective view of a fire pit, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a side wall.

FIG. 10 is a partial enlarged view of an area labeled 10 in FIG. 2 comprising a side wall; and,

FIG. 11 is a perspective view of the fire pit of FIG. 3 wherein the two parts are combined.

The broken lines shown in the drawings are included for the purpose of illustrating portions of the fire pit that form no part of the claimed design.

In FIGS. 2 and 8, the dash dot dot dash broken lines denote the boundaries of the claim and form no part thereof.

The dot-dash broken lines in FIGS. 1, 2 9 and 10 depict the boundaries of the enlargements that form no part of the claimed design.
